PRESSURE EQUALIZER

Emmett Lee Alexander, Enid, Okla., assignor to
 The George E. Failing Supply Company, Enid,
 Okla., a corporation of Oklahoma

Application April 10, 1948, Serial No. 20,265

3 Claims. Cl. 138—30

1

This invention relates to a pressure equalizer for use in the discharge line of a high pressure pump, for example, a mud pump used in circulating drilling fluid during the rotary drilling of a well and has for its principal object to provide an equalizer of this character that smooths out pulsations or surges in the drilling fluid and which reduces or eliminates hammer and line shocks.

Previously the discharge of such pumps were provided with a pneumatic pressure accumulator chamber or dome in which entrapped air acted to cushion pressure pulsations and destructive shocks caused by liquid surges in the discharge line but when such a device is effective at low pressures it is not effective when the pressure is increased for the reason that when the entrapped air is compressed it does not give the desired cushion. This difficulty is overcome in part by equipping the surge chamber with an inflatable bladder that can be preloaded with compressed air at any desired pressure. Therefore, the mud or liquid enters the surge chamber at or above the preloaded pressure and the pressure surges compress the bladder in such a way that the pressure therein is always equal to the line pressures. However, with this arrangement reduction of pump pressure below the preloaded pressure of the bladder again results in pulsations and surge knocks because of the preloaded pressure maintained in the bladder. It is, therefore, a further object of the present invention to provide an equalizer that is substantially uniformly effective throughout the pressure range of such pumps.

In accomplishing these and other objects of the invention as hereinafter pointed out, I have provided improved structure, the preferred form of which is illustrated in the accompanying drawing wherein:

Fig. 1 is an elevation, partly in section, of an equalizer embodying the features of the present invention and showing one of the bladders functioning under low pressure.

Fig. 2 is a similar view showing function of the bladders under high pressures.

Fig. 3 is a cross section on the line 3—3 of Fig. 1.

Fig. 4 is an elevational view partly in section of another form of equalizer embodying the features of the present invention.

Referring more in detail to the drawings:

1 designates a pressure equalizer embodying the features of the present invention and which includes a casing comprising an elongated cylinder 2 provided at the ends with annular flanges 3 and 4 for attaching heads 5 and 6. The heads 5 and 6 each include a dome portion 7 substantially conforming to the diameter of the cylinder 2 and an annular flange portion 8 which seats upon the flanges 3 and 4 for attachment by fas-

2

tening devices such as cap screws 9 that extend through suitable openings 10 in the flanges 8 and into internally threaded openings 11 of the flanges 3 and 4. Inset within the respective ends 5 of the cylinder 2 are seating rings 12 and 13 that are spaced apart to provide a fluid receiving chamber 14 therebetween. The members 12 and 13 are of circular formation and are provided with concave recesses 15 facing the concaved sides of the dome-shaped heads to provide bladder chambers 16 and 17 which connect with the chamber 14 through ports 18 and 19 in the respective seat members. The ports 17 and 18 are preferably covered by grids or perforate plates 20 and 21 having a plurality of apertures 22 through which pressure liquid in the chamber 13 enters the bladder chamber. The grids are preferably of circular formation and are seated within annular shoulders 23 encircling the openings 17 and 18 as shown in Fig. 1.

Mounted in the bladder chambers are bladders 24 and 25 formed of resilient material such as rubber and having an annular wall 26 and preferably curved end walls 27 and 28 corresponding to the curvature in the ends of the compartments. The heads 5 and 6 are each provided with a valve 29 such as ordinarily employed in the inner tube of an automobile and which includes a threaded stem 30 adapted to project through an opening 31 in the heads and secured by a nut 32. The outer ends of the stems may be closed by the usual dust caps 33. The interior of the stems are provided with cores equipped with valving members (not shown) to retain pressure in the respective bladders. Opposite diametrical sides of the cylinder are provided with bosses 34 and 35 having internally threaded openings 36 and 37 for admission of pressure fluid such as the drilling fluid discharged from a mud pump. The equalizer may be mounted on the discharge header of the pump or flow line 38 through which the fluid under pressure is delivered to the drill pipe. When connected with the line 38 the line may be provided with a T fitting 39 and the branch 40 thereof is provided with a nipple 41 that screws within one of the openings 36 or 37 to mount the cylinder.

In the illustrated instance the opposite opening is closed by a plug 42. If desired one section of the flow line may be connected into the opening 36 and the other section into the opening 37 so that the flow is directly through the pressure chamber.

The form of the invention shown in Fig. 4 consists of a pair of cylinders 43 and 44 each having a cylindrical wall 45 and a swaged end 46 merging into a branch 47 at each end of a T-shaped manifold 48. The branch 49 of the manifold is mounted in the pressure flow line. The 55 opposite ends of the cylinders are retained in

spaced relation by a plate 50 which projects laterally from the peripheries of the walls 45 to provide a flange for attaching a head plate 51 by means of fastening devices 52 similar to the fastening devices described. The head plate 49 is provided with dome portions 53 and 54 for closing the open ends of the cylinder compartments and provide abutments for the bladders 55 and 56 which are of similar construction as the bladders previously described. The bladders are retained from blocking inlets to the manifold 48 by means of grid plates 57 and 58 which have openings 59 therein to pass the fluid into the bladder compartments.

In using an equalizer constructed and assembled as illustrated in Figs. 1, 2, and 3 the bladders are charged with compressed air or other compressed fluid to any desired pressure depending upon the range of operating pressures of the pump with which the equalizer is used. The bladders may be inflated by connecting an air hose with the stems of the bladder valves and admitting pressure until the pressure contained therein corresponds with the operating pressure range of the pump. For example, where the operating range is from 35 to 125 pounds, one of the bladders may be inflated to a pressure of 25 pounds and the other 50 pounds. Therefore, when the pump is operating at 35 pounds discharge pressure the bladder having the 50 pound internal pressure is not affected by the pump pressure but the bladder having the 25 pound pressure will be compressed until the air therein is substantially equal to the 35 pound discharge pressure. When the pump pressure is below 50 pounds, pulsations will be smoothed out incidental to compression and expansion of the air in the cylinder having the 25 pound pressure. When the pressure rises above 50 pounds the other bladder will begin to function and take up where the bladder having lower pressure is inefficient to maintain the desired equalizing action on the drilling fluid.

The form of invention illustrated in Fig. 4 operates in the same manner with the exception that the pressure acts through the manifold 46 and through the grids on the respective bladders.

When in use the equalizers need little attention other than an occasional check on the bladder air pressure. If a bladder fails to maintain operating air pressure it is readily removed and replaced with a new bladder by removing the valve core to permit exhausting of air from the bladder, after which the cap screws are removed so that the head may be lifted from its enclosing cylinder to permit removal of the bladder. The bladder may then be readily detached upon removal of the jamb nut 31. A new bladder may then be applied to the head and secured by the jamb nut, after which the projecting end is projected into the open end of the cylinder to permit seating of the head which is again attached by the cap screws 9. The bladder is then inflated with the desired pressure and the operation resumed.

From the foregoing it is obvious that I have provided an equalizer which is of simple and inexpensive construction and which is adapted to function efficiently throughout the operating range of a pump and pressure line with which it is associated.

What I claim and desire to secure by Letters Patent is:

1. A surge equalizer for a flow duct containing

liquid under pulsating flow through a widely variable pressure range including a casing having separate pressure chambers and a pressure transmission passage connecting the flow duct with each pressure chamber, grids separating the pressure chambers from said passage, and a deformable gas filled bladder in each chamber and having portions normally seated on said grids and both of said bladders being simultaneously subject to the same pressures in the flow duct, one of said bladders containing a pressure corresponding to the lower portion of the pressure range and the other containing a pressure corresponding with the upper portion of the pressure range whereby the member having the lower pressure responds to the lower pressure in said flow duct and the member having the higher pressure responds to the higher pressure in equalizing pulsations in said pressure flow.

2. A surge equalizer for a flow duct containing liquid under pulsating flow through a widely variable pressure range including a casing having separate pressure chambers in opposed coaxial relation, said casing having connection with the flow duct at a point intermediate the pressure chambers, grids spaced apart within the casing and providing a space between the pressure chambers in connection with said passage, and a deformable gas filled bladder in each chamber and having portions normally seated on said grids and both of said bladders being simultaneously subject to the same pressures in the flow duct, one of said bladders containing a pressure corresponding to the lower portion of the pressure range and the other containing a pressure corresponding with the upper portion of the pressure range whereby the member having the lower pressure responds to the lower pressure in said flow duct and the member having the higher pressure responds to the higher pressure in equalizing pulsations in said pressure flow.

3. A surge equalizer for a flow duct containing liquid under pulsating flow through a widely variable pressure range including a casing having laterally spaced parallel pressure chambers, a manifold connecting said pressure chambers and providing a pressure transmission passage connected with the flow duct, grids separating the pressure chambers from said passage, and a deformable gas filled bladder in each chamber and having portions normally seated on said grids and both subject to the same pressures in the flow duct, one of said bladders containing a pressure corresponding to the lower portion of the pressure range and the other containing a pressure corresponding with the upper portion of the pressure range whereby the member having the lower pressure responds to the lower pressure in said flow duct and the member having the higher pressure responds to the higher pressure in equalizing pulsations in said pressure flow.
